UNITED STATES PATENT OFFICE.

CHARLES ANDERSEN, OF NEW ROCHELLE, NEW YORK.

PULLEY-BLOCK.

970,978.

Specification of Letters Patent. Patented Sept. 20, 1910.

Application filed November 27, 1909. Serial No. 530,280.

To all whom it may concern:

Be it known that I, CHARLES ANDERSEN, a citizen of the United States of America, residing at New Rochelle, in the county of 5 Westchester and State of New York, have invented new and useful Improvements in Pulley-Blocks, of which the following is a specification.

This invention relates to pulley blocks, 10 and one of the principal objects of the same is to provide simple means for permitting a rope to be applied to the pulley without requiring the end to be reaved through over the grooved roller in the block.

15 Another object of the invention is to provide a pulley block having means for supporting the same and an arm pivoted to the block and adapted to be swung outwardly to permit a bight of the rope to be passed 20 into the pulley without requiring the end to be fed through over the grooved roller in the block.

25 These and other objects may be attained by means of the construction illustrated in the accompanying drawing, in which,—

Figure 1 is a side elevation of a pulley block made in accordance with my invention. Fig. 2 is a longitudinal sectional view of the same, showing the pivoted arm swung 30 outward in dotted lines.

Referring to the drawing, the numeral 1 designates the pulley block preferably comprising separate plates or supports having a spacing member 2 at the lower end thereof secured to the block members by means of screws 3 extending through the block members and the spacing member 2. Pivotally mounted in the members in the block 1 is a 35 grooved roller 4 mounted on a pintle 5 journaled in the block in the usual manner. The upper ends of the members 1 are provided with bearings 6, 7, and connected to the bearing 6 is a supporting device 8 having connected to its upper end a curved and grooved support 9 through which the rope 40 or cable 10 extends. An arm 11 is pivoted upon the bearing 7 and is provided with a stud 12 which projects through an aperture in the member 8, said stud being formed 45 upon a cross bar 13 on the member 11. A square pin 14 extends through the member

8, through the support 9 and through the squared aperture 15 in the pivoted member 11. The outer end of the pin 14 is provided with an eye 16 through which a cotter pin 55 17 is passed to hold the parts in locked position. The cotter pin 17 is connected to a cord or chain 18 secured to the member 11 at 19 to prevent the loss of the cotter pin.

The operation of my invention may be 60 briefly described as follows: When it is desired to connect a rope *a* to the block the pin 17 is withdrawn, and the member 11 is thrown outward to the dotted line position shown in Fig. 2, after which a bight in the 65 rope *a* may be passed over the member 11 and around the grooved roller 4. The member 11 is then swung back into position, and the pin 17 is passed through the eye 16.

From the foregoing it will be obvious that 70 a pulley block made in accordance with my invention will save much time in securing the rope in the block, since it does not require feeding the end of the rope through over the grooved roller 4.

75 My invention is simple in construction, can be manufactured at low cost, is strong, durable and efficient in use, and is made of few parts not liable to get out of order.

I claim:—

1. A pulley block having a grooved roller, an apertured supporting arm, a grooved support connected thereto, an arm pivoted to the block and provided with a stud to engage the aperture in the supporting arm, a pin 85 extending through the supporting arm and support and through the pivoted arm, and retaining means for engaging said pin to hold the pivoted arm in place.

2. A pulley block comprising spaced 90 plates, a roller supported by the plates, a support located above the roller and comprising separable members pivotally connected with the said spaced plates, and retaining means for holding the separable 95 members against separation.

In testimony whereof I affix my signature in presence of two witnesses:

CHARLEY ANDERSEN.

Witnesses:

JOHN OLSEN,
GEO. G. SUTHERLAND.
